Primary Examiner — Derrick E Holland

(57) **CLAIM**

The ornamental design for a handle for solar panels, as shown and described.

DESCRIPTION

FIG. 1 is a front elevation view of a first component of a handle for solar panels embodying my new design; FIG. 2 is a rear elevation view thereof; FIG. 3 is an enlarged left side elevation view thereof; FIG. 4 is an enlarged right side elevation view thereof; FIG. 5 is a top plan view thereof; FIG. 6 is a bottom plan view thereof; FIG. 7 is a front elevation view of a second component of the handle for solar panels embodying my new design; FIG. 8 is a rear elevation view thereof; FIG. 9 is an enlarged left side elevation view thereof; FIG. 10 is an enlarged right side elevation view thereof; FIG. 11 is a top plan view thereof; FIG. 12 is a bottom plan view thereof; FIG. 13 is a perspective view of the handle for solar panels with the first and the second components combined together; FIG. 14 is another perspective view thereof; FIG. 15 is an enlarged view of the selected portion 15 in FIG. 13; FIG. 16 is a front elevation view thereof; FIG. 17 is a rear elevation view thereof; FIG. 18 is an enlarged left side elevation view thereof; FIG. 19 is an enlarged right side elevation view thereof; FIG. 20 is a top plan view thereof; and, FIG. 21 is a bottom plan view thereof.

The broken lines shown in the figures depict portions of the handle for solar panels that form no part of the claimed design.
